LIFE RAFT

Ralph L. Miller, Randolph, Ohio, and Charles J. Ford, South Bend, Ind., assignors to The Goodyear Tire & Rubber Company, Akron, Ohio, a corporation of Ohio

Application October 24, 1957, Serial No. 692,077

17 Claims. (Cl. 9—11)

This invention relates to inflatable life rafts and particularly to the type in which the buoyant portion of the raft comprises one or more endless inflatable elements surrounding the occupant receiving space, with a floor of fabric or the like joined to the said buoyant portion in an annular zone at or near the mid-plane of the latter, so that the raft when inflated possesses substantially the same serviceability with either side up.

Rafts of the above mentioned type are of particular use as emergency escape craft from aircraft which may be forced down at sea as well as for use with water-borne craft. Such a raft has the distinct advantages over a rigid hull type boat of requiring relatively small storage space, being light, and, therefore, easily transportable, and also requiring no complex launching apparatus. However, in many uses, particularly where the prospective occupants are not experienced in water disciplines, difficulties have been encountered in providing comfortable accommodations with maximum safety but, nonetheless, minimum boarding difficulties. The use of high freeboard rafts in order to provide safety and comfort has, in the past, resulted in problems in providing for boarding or entrance into the raft from the water. Conversely, modifications such as deflatable freeboard sections or rigid ladders to provide easier boarding have resulted in a decrease in the safety of the craft and a decrease in its hull integrity as well as making storage and use more difficult.

Ladders affect not only storage requirements but in some constructions cause an unbalance of the raft when an attempt is made to board which may be serious enough to cause the raft to flip over on to the boarder. Deflatable sections for boarding stations seriously weaken the raft structure when deflated and in a running sea permit the raft to buckle, making boarding difficult and allowing water to enter the occupant area.

It is a major object of this invention to provide a raft of the type described which has high freeboard for comfort and safety and at the same time provides for ease of boarding the raft.

It is a further object of this invention to provide a boarding station which does not affect the rigidity of the raft structure or increase its bulk so as to require greater storage space.

It is a still further object of the present invention to provide a boarding station by which an occupant can enter the raft unassisted and yet, where an injured person must be taken aboard, permit an occupant to bring him aboard with minimum difficulty and maximum safety to the occupant.

These and other objects will become apparent from the following description and drawings in which:

Fig. 1 is a plan view of a raft constructed according to the present invention;

Fig. 2 is a section along line 2—2 of Fig. 1 illustrating the arrangement of a boarding station;

Fig. 3 is a plan view of another type of raft constructed according to the present invention;

2

Fig. 4 is a plan view of still another type of raft constructed according to the present invention;

Fig. 5 is a full section of the raft taken along the line 5—5 of Fig. 4; and

Fig. 6 is a section of a raft illustrating a further modification of the boarding station; and

Fig. 7 is a partial section of still another design according to the present invention.

Referring to the figures, the buoyancy elements of the 10 raft comprise annular inflation chambers 1 and 2 having a horizontal deck 3 of fabric or the like extending along the mid-plane between them. The inflation chambers are conventionally inflated by two compressed gas cylinders 4, each rail or chamber having its own inflation bottle. 15 The raft may have the usual equalizer tubes between the chambers to assure equal inflation pressure therein, if so desired. The raft has a center stowage locker 5 having a mast mount 6 substantially centrally thereof. The area 5 is used to stow protective curtains etc., which when 20 rigged with a mast adapted to fit the mount 6 may be suitably arranged at the peripheral edges of the upper buoyancy chamber to provide shelter for the occupants. Other conventional aids, such as heaving lines, bailing buckets, etc. are suitably arranged so as to be accessible 25 to the occupants.

In Fig. 1, the raft comprises two buoyancy sections 1 and 2 which are made of a series of segments defining an irregular polygon whose envelope is substantially an ellipse. The sections 1 and 2, while symmetrical with 30 respect to each other, are rotated relative to each other in the horizontal plane through an arc of 90 degrees whereby at each ninety degree point, one or the other of the buoyant sections extends outwardly or overhangs the other. These overhang sections provide the boarding station locations 7. As can be seen in Fig. 1, the stations are in opposite pairs which are inverted with respect to the adjacent stations so that regardless of which side of the raft is up when it is launched, two boarding points at opposite sides of the raft are available to prospective occupants for entry onto the raft. The arrangement of and the offset relationship between the buoyant sections 1 and 2 can be more clearly seen in Fig. 2. As an aid to 35 entry, a small inflatable step section 8 is provided substantially at the waterline of the lower main buoyance section 2. A similar step member is provided at the adjacent boarding station, being, of course, inverted with respect to the other in order to provide a step when the raft is other side up. Further boarding aids such as the hand grips 9 are provided at each station.

It can be seen that the offset relationship of the buoyant sections provides a convenient, accessible boarding point while maintaining the essential high freeboard of the raft and without increasing the storage space of the deflated raft to any substantial degree. Further, the offset relationship does not affect the structural integrity of the raft as do separately deflatable and inflatable boarding stations of the prior art. It is obvious, of course, that a greater number of superimposed buoyant sections could be utilized if desired to increase the freeboard height and it would merely be necessary to horizontally displace some of the adjacent sections or rotate some sections through the desired arc to form a boarding station in such a raft.

In Fig. 3 is shown a raft in which the offset relationship of the buoyant sections at the boarding station 10 is 65 provided by constructing the buoyant sections in an unsymmetrical shape having at least one inset section such as at 11. Thus in smaller rafts, and those having regular polygonal shapes, where rotation of the buoyant sections with respect to each other would not provide adequate offset for boarding, a simple yet efficient station can nonetheless be provided. The raft in Fig. 3 has a deck

12 of fabric or the like and a central stowage space 13 similar to the raft of Fig. 1. The boarding stations 10 may, of course, be provided with a step section 14 and hand grips 15 similar to those previously described.

A further modification of a raft to provide a boarding station is illustrated in Fig. 4. Here a raft having regularly shaped buoyant sections 16 and 17 is provided with boarding stations by translating one section with respect to the other rather than rotating them or building an inset into the sections.

The relationship of the sections may be more clearly seen in Fig. 5. Boarding stations 18, inverted with respect to each other, are provided by the translatory movement of section 16 with respect to section 17. The stations may, of course, be provided with the step section 19 and hand grips 20 as previously described. The central stowage area 21 is provided with mast moorings 22 and 23, which are offset with respect to each other in order to center the mast no matter which side of the raft is up. The stowage area is constructed with a hollow tube 24 surrounding the area and inflatable by means of valves 25. The valves may be disposed on the left and right as shown or in some cases it may be desirable to place them one over the other at opposite surfaces of the tube. A rubberized fabric deck 26 spans the area encircled by the tube to retain the watertight integrity of the stowage space.

Fig. 6 illustrates a modification of a boarding station in which the inflatable step section is replaced by a rung 27 suspended below the waterline and attached to the buoyant section 28 by straps or hangers 29. The usual hand grips 30 may be provided as desired.

It is clear that an offset type boarding station may be provided in any multi-section raft by the means described. That is, in rafts of elongated sections, the sections may be rotated with respect to each other through the desired arc. In rafts having regular polygonal or circular sections they may be constructed with an inset portion as described with respect to Fig. 3 or the sections may be linearly displaced with respect to each other as described with respect to Figs. 4 and 5. Various types of step sections, boarding rungs and hand grips may, of course, be provided as necessary or desired. An example of a boarding station in a raft having a larger number of sections is illustrated in Fig. 7. The raft comprises a plurality of sections 31, 32, and 33 having some of the sections displaced with respect to others to provide a boarding station, as for example sections 31 and 33 which are mutually displaced with respect to section 32 and each other. Of course, a suitable step member 34 and boarding straps 35 may be provided in a manner similar to the other embodiments illustrated.

While certain representative embodiments and details have been shown for the purpose of illustrating the invention, it will be apparent to those skilled in this art that various changes and modifications may be made therein without departing from the spirit or scope of the invention.

I claim:

1. A raft comprising an endless buoyant sidewall structure defining a closed area and including a plurality of endless buoyant sections in superimposed relationship with at least a part of at least one of said buoyant sections disposed in horizontally displaced relationship with respect to another of said sections to form at least one boarding station for the said raft, and a deck spanning said closed area and being attached to said sidewall structure substantially along the midplane horizontally thereof.

2. A raft as claimed in claim 1 in which said boarding station is provided with a step member substantially at or below the waterline of the buoyant section in the water.

3. A raft comprising an endless buoyant sidewall structure defining a closed area, said sidewall structure including a plurality of buoyant endless sections in super-

imposed relationship, with some of said sections being disposed in horizontally displaced relationship at least in part with respect to others to form at least one boarding station for the said raft, and a deck spanning said closed area and being attached to said sidewall structure substantially along the midplane horizontally thereof.

4. A raft as claimed in claim 3 in which said boarding station is provided with a step member substantially at or below the waterline of the buoyant section in the water.

5. A raft comprising an endless buoyant sidewall structure defining a closed area, said sidewall structure including two congruent buoyant sections in superimposed relationship and disposed in horizontally displaced relationship with respect to one another to form at least one boarding station for said raft regardless of which section is in the water, and a deck spanning said closed area and being attached to said sidewall structure substantially along the horizontal midplane thereof.

6. A raft as claimed in claim 5 in which said sections define a polygon and said sections are rotated horizontally through an arc with respect to each other to provide the said displacement.

7. A raft as claimed in claim 5 in which said sections are horizontally translated with respect to each other to provide the said displacement.

8. A raft as claimed in claim 5 in which said boarding station is provided with a step member substantially at or below the waterline of the section in the water.

9. A raft comprising an endless buoyant sidewall structure defining a closed area, said sidewall structure including two buoyant sections in superimposed relation, each of said sections defining an elongated polygon whose envelope substantially defines an ellipse and said sections disposed in horizontally displaced relationship with respect to each other to form at least one boarding station for said raft regardless of which section is in the water, and a deck spanning said closed area and being attached to said sidewall structure substantially along the horizontal midplane thereof.

10. A raft as claimed in claim 9 in which said sections are rotated through a horizontal arc with respect to each other to provide the said displacement.

11. A raft as claimed in claim 9 in which said sections are horizontally translated with respect to each other to provide the said displacement.

12. A raft as claimed in claim 10 in which the said boarding station is provided with a step member substantially at or below the waterline of the section in the water.

13. A raft as claimed in claim 11 in which the said boarding station is provided with a step member substantially at or below the waterline of the section in the water.

14. A raft comprising an endless buoyant sidewall structure defining a closed area, said sidewall structure including two congruent buoyant sections in superimposed relation, each of said sections defining a polygon whose envelope curve substantially defines an ellipse with said sections disposed in a rotationally displaced relationship of substantially 90 degree arc in the horizontal plane with respect to each other to form at least one boarding station for said raft regardless of which section is in the water, and a deck spanning said closed area and being attached to said sidewall structure substantially at the horizontal mid plane thereof.

15. A raft as claimed in claim 14 in which the said boarding station is provided with a step member substantially at or below the waterline of the section in the water.

16. A raft comprising an endless buoyant sidewall structure defining a closed area and including a plurality of endless buoyant sections in superimposed relationship with at least a part of at least one of said buoyant sections disposed in horizontally displaced relationship with respect to another of said sections so that a portion of a buoyant section adjacent the waterline extends outwardly from a portion of an adjacent superimposed section to

form at least one boarding station for the said raft, and a deck spanning said closed area and being attached to said sidewall structure substantially along a plane horizontally thereof.

17. A raft comprising an endless buoyant sidewall structure defining a closed area, said sidewall structure including two congruent buoyant sections in superimposed relationship and disposed in horizontally displaced relationship with respect to each other so that a portion of a buoyant section adjacent the waterline extends out-

wardly from an adjacent superimposed section to form at least one boarding station for said raft regardless of which section is in the water, and a deck spanning said closed area and being attached to said sidewall structure substantially along a plane horizontally thereof.
